CAN AND BOTTLE CRUSHER

Fred J. Mingo, Cleveland, Ohio

Application June 2, 1949, Serial No. 3,015

Term of patent 3½ years

(Cl. D55—1)

To all whom it may concern:

Be it known that I, Fred J. Mingo, a citizen of the United States, residing at Cleveland, county of Cuyahoga, and State of Ohio, have invented a new, original, and ornamental Design for a Can and Bottle Crusher, of which the following is a specification, reference being had to the accompanying drawing, forming a part hereof.

Fig. 1 is an elevational view of one side of a can and bottle crusher embodying my new design;

Fig. 2 is an elevational view of the other side of the can and bottle crusher; and

Fig. 3 is a front elevational view of the can and bottle crusher.

I claim:

The ornamental design for a can and bottle crusher, substantially as shown.

FRED J. MINGO.
